UNITED STATES PATENT OFFICE.

CHARLES W. DAKE, OF CHICAGO, ILLINOIS, ASSIGNOR TO PYLE-NATIONAL ELECTRIC HEADLIGHT COMPANY, OF CHICAGO, ILLINOIS, A CORPORATION OF NEW JERSEY.

TURBINE.

1,098,319.

Specification of Letters Patent. Patented May 26, 1914.

Application filed August 4, 1913. Serial No. 782,978.

To all whom it may concern:

Be it known that I, CHARLES W. DAKE, a citizen of the United States, residing at Chicago, in the county of Cook and State of Illinois, have invented a certain new and useful Improvement in Turbines, of which the following is a specification.

My invention relates to improvements in turbines and is illustrated in the accompanying drawing which shows diagrammatically a sectional view with parts broken away and parts omitted of a turbine embodying my invention.

Like parts are indicated by the same letters in the figure.

The turbine housing A completed by a cap or end A¹ contains the bearings A² in which rotate the shaft A³. The hub B on the shaft A³ carries a body B¹ upon which are mounted the turbine buckets B² held in position by lugs B³ and rings B⁴. A steam nozzle C fed through a stem passage C¹ with steam from any suitable source of supply not indicated feeds the steam into the buckets 25 and rotates the turbine.

D is a bearing or guard ring projecting inwardly from the housing A and closely surrounding the outwardly extended edge or rim D¹ of the body B¹. This rim D¹ in the present instance extends out beyond the edge of the buckets although it might not extend so far, in which case the ledge or ring D would necessarily extend farther inward to bring it into the two parts in the same relative position. The purpose of parts D and D¹ is obvious. Bearings such as these are designed have high speed and heavy duty. They are frequently improperly cared for and not adequately inspected. It often happens that the bearings wear out. The turbine wheel then gets off center and there is a possibility that the buckets will scrape on the steam nozzle thus breaking or bending the buckets, cutting down the efficiency 45 of the machine if not actually stopping it

and adding greatly to the cost of repair. In my improved form, when this wear of the bearings take place, the body or bucket wheel will be still centered within reasonable limits by the collar D supporting the bucket wheel as the periphery D¹ thereof comes in contact therewith, thus wearing away or breaking up of the buckets is entirely prevented.

It will be evident that my invention is not to be limited to any precise or particular arrangement of parts. It is conceivable that the supporting ring in the housing might be differently positioned or differently sized, and it is sufficient that it be of such size as to adequately support the rotor and that the rotor has a cylindrical surface concentric therewith for the purpose of coming into contact therewith at the appropriate time, and I wish therefore that my drawing be regarded as in a sense diagrammatic.

I claim:

1. In a turbine having a rotor, buckets thereon and a fluid supply nozzle, a housing, the clearance between said housing and said rotor being less than the clearance between said nozzle and the buckets.

2. A turbine comprising a housing, a ring thereabout, a rotor body, a row of buckets projecting therefrom and a nozzle, the clearance between the nozzle and the buckets being greater than the clearance between the ring and the body.

3. A turbine having a rotor, buckets thereon, a fluid supply nozzle, and a guard in opposition to said rotor, the clearance between said guard and the rotor being less than the clearance between the nozzle and the buckets.

In testimony whereof, I affix my signature in the presence of two witnesses this 26th day of July, 1913.

CHARLES W. DAKE
